B. BENEDICT.
PORTABLE ELECTRIC LIGHT.
APPLICATION FILED JULY 19, 1917.

1,246,225.

Patented Nov. 13, 1917.

UNITED STATES PATENT OFFICE.

BERNARD BENEDICT, OF NEW YORK, N. Y., ASSIGNOR TO NATIONAL CARBON COMPANY INC., OF NEW YORK, N. Y., A CORPORATION OF NEW YORK.

PORTRABLE ELECTRIC LIGHT.

1,246,225.

Specification of Letters Patent. Patented Nov. 13, 1917.

Application filed July 19, 1917. Serial No. 181,509.

To all whom it may concern:

Be it known that I, BERNARD BENEDICT, a citizen of the United States, residing at New York city, in the county of Bronx and 5 State of New York, have invented certain new and useful Improvements in Portable Electric Lights, of which the following is a specification, reference being had therein to the accompanying drawings, forming part 10 thereof.

My invention relates to self-contained or battery-operated portable electric lights and relates more particularly to those having flat casings and in which the lamp is exposed at 15 the side of the casing forming the front of the device. Objects of my invention are to provide a light of this kind which is simple in construction, inexpensive of manufacture, durable, dependable, which is adapted to a 20 wide range of uses and which is more particularly adapted to the needs of soldiers, and also equally suitable for use by everyone, under varying conditions and circumstances. Other and more particular objects and 25 advantages of my invention will hereinafter appear.

My invention includes novel circuit-completing and circuit-controlling means, and also includes such means in combination with 30 other features, and further includes features of construction and combinations of parts, as will appear from the following description.

I shall now describe the portable electric 35 light illustrated in the accompanying drawings embodying my invention and shall thereafter point out my invention in claims.

Figure 1 is a front elevation of one embodiment of the complete portable electric 40 light.

Fig. 2 is an elevation of the same as viewed from the left in Fig. 1.

Fig. 3 is a central longitudinal section on a vertical plane indicated by the line 3—3 of 45 Fig. 1 as viewed from the left, with the battery and lamp appearing in elevation.

Fig. 4 is a rear elevation as viewed from the left in Figs. 2 and 3, but with the hinged casing door open.

Fig. 5 is a plan view of the complete device as viewed from above in Fig. 1.

Fig. 6 is an enlarged partial longitudinal section on a vertical plane indicated by the line 6—6 of Figs. 2 and 3 as viewed from the

left, and shows the upper part of the device from the rear.

Fig. 7 is a similar view on a plane indicated by the line 7—7, showing the lower part of the device from the rear.

Fig. 8 is a greatly enlarged partial longitudinal section on a vertical plane indicated by the line 8—8 of Figs. 2 and 3 as viewed from the right and of Fig. 5 as viewed from below.

Fig. 9 is a similar transverse section on a horizontal plane indicated by the line 9—9 of Fig. 6 as viewed from above.

Fig. 10 is an elevation, as viewed from the right inwardly of the casing in Fig. 3, of a spring circuit-completing bridge which is 70 carried by the upper part of the hinged door at the inside of the casing and which appears in transverse horizontal section in Fig. 9.

Fig. 11 is a partial elevation as viewed 75 from the right, of what appears in the lower part of Fig. 4.

The portable electric light embodying my invention illustrated in the accompanying drawings, has a flat substantially rectangular 80 elongated sheet metal battery-containing and lamp-supporting casing box 1, shown as rounded laterally at the front, and as having its other corners slightly rounded, and as provided at the back with a flat 85 sheet metal closure or door 2 which is hinged at the bottom on pivots 3 to open angularly rearward and downward, and which at the top is provided with a projecting spring tongue forming a latch 4 which 90 is engageable with a catch 5 shown as formed at the top and rear of the casing part 1 by indenting outward the sheet metal thereof, as clearly appears in the drawings. The casing 1 is shown as provided with outwardly indented stiffening ribs 6 and 7, at 95 the front and at the edges or margins thereof, respectively.

A metallic outwardly concave reflector 8 is fixedly carried by the casing 1 and is 100 firmly secured in an opening provided in the upper margin of the front flat side of the casing 1, and extends inwardly of the casing, where it is centrally provided with a usual form of metallic screw-threaded lamp socket 105 9, which is shown as formed in one piece with the reflector 8. The reflector 8 has an outer annular or circular screw-threaded

part 10 which projects forward from and at the outside of the front of the casing 1, and is shown as provided with a slight inturned flange upon which rests the marginal edge of a lens 11, which is held in place by a usual form of annular screw-threaded band or ring 12, which is screwed over the outer projecting screw-threaded end part 10 of the reflector, and at its outer edge or margin is provided with a slight inturned flange for engaging the margin of the lens 11, as appears in the drawings, particularly in Fig. 3. A usual miniature incandescent lamp has its usual screw-threaded metallic base 13 screwed into and in electrical connection with the metallic lamp socket 9 and has its bulb 14 exposed at the front of the reflector 8 toward the outside of the flat side of the casing 1, and has its central terminal 15 exposed at the inside of the casing 1 in proximity and in spaced relation to the inner surface of the hinged door 2, as most clearly appears in Fig. 3 of the drawings.

The sheet metal casing, comprising the main box-like casing part 1 having at the back the hinged door 2, is adapted to contain a usual flat form of dry battery 16, below the reflector 8, the battery 16 having a usual short substantially upright spring contact terminal 17 and also having a usual longer spring contact terminal 18, which in this particular battery 16 is also shown as extending or projecting substantially upward. By reason of the transverse position of the lamp its central terminal 15 is not so located as to be engaged by the longer spring battery terminal 18, as will appear from the drawings, particularly Figs. 3 and 4, and circuit-completing means involving my invention are provided for completing the electrical connection between the longer battery terminal 18 and the central terminal 15 of the lamp, and such means will now be described.

45 A circuit-completing metal plate, having a horizontally arranged body part 19, is supported by and insulated from the upper horizontal top wall of the box-like casing part 1 at the inside thereof. Two layers 50 of insulation, comprising a comparatively heavy and strong lower or inner insulating plate 20 and an upper insulating plate 21, are interposed between the upper surface of the conductive plate 19 and the inner surface 55 of the top wall of the metallic casing 1. The metallic circuit-completing plate 19 is firmly secured to the lower or inner thick and strong insulating plate 20 by metallic rivets 22, shown as two in number and of the tubular or eyelet form, and which are insulated from the top wall of the metallic casing box 1 by the interposed upper insulating plate 21. The two superposed insulating plates 20 and 21 are firmly secured to the inner surface 65 of the top of the metallic casing 1 by

means of a pair of strong tubular rivets or eyelets 23 adjacent to the ends of these insulating plates, so that the circuit-completing plate 19 is supported by and insulated from the horizontal top of the metallic casing box 70 1 at the inside thereof, as appears in the drawings, particularly in Fig. 8.

The circuit-completing plate 19 is shown as provided with a contact-making end part 24, which is reversely bent in U-shape from the left end of the strip or plate 19 as viewed from the rear of the casing and as appears in Fig. 4 of the drawings, this end part 24 being in a position to be firmly engaged by the upper end of the longer spring terminal 80 18 of the battery under suitable circuit-making spring tension of the terminal 18, which is sprung or bent laterally and downward as appears in the drawings, particularly in Fig. 4. The projecting contact springs or terminals of batteries such as the battery 16 are not always of exactly or precisely the same length, and it is to be noted that the contact-making end part 24 of the circuit-completing plate 19 provides for the 90 accommodation of a spring battery terminal of a different length, and particularly of somewhat shorter length, than the longer terminal 18 illustrated in the drawings. At its other end and at a point substantially in line with and above the central terminal 15 of the lamp, the circuit completing plate or strip 19 is provided with a downwardly turned lateral extension or projection 25, which extends substantially parallel with and in proximity to, but is substantially spaced from, the inner surface of the flat wall of the substantially flat metallic door 2, as is clearly shown in the drawings in Figs. 3 and 4. It will now be understood that the circuit-completing plate 19, having the projecting contact-making ends 24 and 25, forms an electrically conductive extension from the longer battery terminal 18, this circuit-completing plate being supported by and 100 insulated from the top of the casing box 1.

For bridging the gap and completing the electrical connection from the downwardly turned projection 25 of the circuit-completing member 19 to the inwardly exposed central terminal 15 of the lamp, a circuit-completing bridge is provided and is shown as carried by and insulated from the upper part of the hinged door 2 at the inside thereof and is shown as comprising a short vertically extending spring metal strip 26, this resilient bridge piece 26 being comparatively thin and flexible. The thin resilient bridge strip 26 is firmly secured at an intermediate point thereof, shown as slightly above its middle, by means of a tubular metallic rivet 27, to a small transversely extending insulating plate 28, shown as of a width which is the same as the length of the resilient bridge piece 26 and as projecting laterally 120 130

at the edges of this bridge piece, as appears in the drawings in Figs. 3, 9 and 10. A second small insulating plate 29, similar to and shown as coextensive with the insulating plate 28, is interposed between the latter and the adjacent inner face of the metallic door 2 and serves to insulate the bridge-securing eyelet 27 from this metallic door. At their laterally projecting ends the superposed insulating plates 28 and 29 are firmly secured to the flat inner side of the door 2 by means of tubular metallic rivets or eyelets 30 which pass through both of the insulating plates 28 and 29, and through the metallic door 2, as is shown most clearly in Fig. 9 of the drawings. The free projecting upper and lower end parts of the thin resilient bridge 26 are offset in spaced relation to the adjacent insulating plate 28, by which this bridge member is supported, and these ends are exposed in position to come in contact, respectively, with the downwardly projecting part 25 of the circuit-completing member or plate 19 and with the central terminal 15 of the lamp, when the door 2 which carries the bridge 26 is in the closed position, as clearly appears in Fig. 3 of the drawings.

A manually operable circuit-controlling device embodying features of my invention is provided for electrically connecting the shorter upright battery terminal 17 with the metallic casing box 1 for thereby completing the circuit of the battery 16 through the lamp, and this circuit-controlling device will now be described.

A comparatively flexible and resilient metallic circuit-controlling strip 31, forming an automatically-returning circuit-controlling lever, is shown as secured at its upper horizontally extending end to the inner insulating plate 20 by means of a tubular metallic rivet or eyelet 32 which extends only through the metallic strip 31 and through the insulating supporting plate 20 and is insulated from the metallic top of the casing box 1 by the upper interposed insulating plate 21, so that this circuit-controlling spring metal strip 31 is supported by and insulated from the top of the metallic casing box 1. The circuit-completing or contact-making strip 31 is bent downward on a curve at the right of its securing rivet 32, as viewed from the open back of the casing 1 in Fig. 4, and also as seen in Fig. 8, and projects downward at a slight inclination or at a slightly obtuse angle to the insulating plate 20. At its lower end the flexible-resilient circuit-controlling lever-forming strip 31 overlaps upon and at the outer side of, but in spaced relation to, the short upwardly and slightly inwardly projecting battery terminal 17, as is clearly illustrated in Fig. 4 of the drawings.

A manually operable device movably sup-

ported by the casing is provided and is adapted when operated to engage and press upon the resilient lever-forming contact strip or contact spring 31 at an intermediate point thereof, for thereby shifting its free lower end into circuit-completing contact with the shorter upright battery terminal 17, and this manually operable device is shown as a circuit-controller of substantially usual form. This manually operable circuit-controller also serves at the same time or concurrently electrically to connect the flexible contact spring 31 with the metallic battery-containing casing box 1, whereby the circuit of the lamp through the battery will be completed. A metallic spring contact strip 33 is shown as secured at its lower end, by means of a small rivet 34, to the inside of the margin of the battery-containing casing box 1, and at its upper free end 35 this spring strip 33 is turned inward and slightly downward toward but normally out of contact with or having its end spaced from the downwardly projecting contact-making spring lever 31, as is clearly shown in Fig. 4 of the drawings, and forms an automatically-returning circuit-controlling member. It is to be noted in this connection that the free inwardly projecting upper end 35 of the contact strip 33 is in proximity to but spaced from the downwardly projecting spring lever 31 at an intermediate point thereof, which is shown as at a location somewhat above the middle of the downwardly inclined part of the spring lever 31, this point being nearer to the insulating plate 20, to which the contact-spring 31 is secured, than it is to the lower free movable end of this spring lever 31, as clearly appears in Fig. 4 of the drawings.

Adjacent to its inturned upper end 35 the contact-strip 33 is provided at the outer side thereof with a push button 36 which projects through an opening in the casing box 1 to the outside thereof for manual actuation in a usual way. Also the spring-contact strip 33 is adapted to be actuated by a usual slide 37 which is guided in a usual way on the casing box 1 and which is adapted to ride over and push in the projecting rounded outer end of the push button 36 in a usual way, for thereby obtaining a prolonged or an indefinitely closed circuit condition of the lamp through the battery 16, as is well understood in the art. It is to be noted that the lower end of the slightly inclined downwardly projecting circuit-controlling spring lever 31 is disposed inwardly from and in spaced relation to the adjacent surface of the spring-contact strip 33, so that this free movable end of the circuit-controlling spring lever 31 occupies a position intermediate between and out of contact with both the metallic contact-strip 33 and the short upright battery terminal 17.

The comparatively large size and inwardly projecting arrangement or location of the reflector 8 necessitates the provision of considerable room or space above the battery 16 between the upper end of the battery and the top wall of the battery-containing casing box 1, and the circuit-completing lever formed by the angularly movable flexible downwardly projecting contact-spring 31 serves among its other important functions, to bridge the gap between the inturned end 35 of the usual spring-contact strip 33 and the usual short upright battery terminal 17, as will be readily understood from an inspection of the drawings, particularly Fig. 4 thereof. However, it is to be noted in this connection that the downwardly projecting spring circuit-controlling lever 31 has other important functions and advantages now to be noted. It should be noted that by reason of the employment of this intermediately located circuit-completing member 31, that in the open circuit condition of the device as shown in the drawings, there occur two breaks in the circuit, or that is to say the lamp circuit is opened at two places between the free in-turned end 35 of the usual circuit-controlling contact-strip 33 and the usual short upright battery terminal 17, one of these breaks or places where the circuit is opened being between the end 35 of the contact-strip 33 and the downwardly projecting circuit-controlling spring lever 31, and the other break or place of open circuit occurring between the lower free end of the circuit-controlling spring lever 31 and the battery terminal 17. This breaking or opening of the lamp circuit at two places or points provides an additional measure of security against an accidental closed circuit condition, which might possibly result through some disarrangement of the parts, it being very improbable that any damage by reason of the bending or other disarrangement of the circuit-controlling members could occur which would concurrently accidentally close the circuit at both of these places. Furthermore, in this connection it is to be noted that the resilient flexible circuit-controlling strip or spring lever 31 acts as a lever of the third class in its circuit-closing operation, and that the inward movement of the free inturned end 35 of the movable contact-strip 33 imparts an increased or multiplied movement to the lower free end of the flexible circuit-controlling spring lever 31, thereby rendering it possible to provide for a large circuit-controlling movement and a correspondingly wide gap or space between the contact terminals in the open circuit condition, particularly between the movable free end of the downwardly projecting flexible contact-spring or lever 31 and the upstanding short battery terminal 17, whereby the liability of

accidental or unintentional closure of the circuit is further lessened.

Supporting means or carrying means for the device, now to be described, are provided and involve features of novelty, particularly as combined with other features of my invention. A small bail 38 is pivoted to the top of the casing box 1 near the front thereof, and is shown as having its outwardly indented ends inserted into outwardly indented sockets 39 on the top of the casing part 1. The bail 38 among its other functions or uses has the usual one, in that it provides for carrying the device as a lantern, with a finger or fingers through the bail. The bail 38 is adapted to fold rearward over or across the upper end of the door 2 in the closed position of the latter, as appears in Figs. 1, 2, 3, 5 and 6 of the drawings.

The side arms of the bail 38, which are shown as parallel to each other, are rather sharply bent at a point adjacent to the connecting cross-bar or handle-bar of the bail, so that in the folded condition of the bail this connecting handle-bar thereof will be disposed slightly below the upper end of the casing box 1 and door 2 and also slightly spaced in a backward direction from the outer surface of the upper end of the door 2, the side arms of the bail being of the correct length for accomplishing this result, and also so that the side arms of the bail 38, at the downward bend therein, will engage and press inwardly upon the upper end of the door 2 at the back thereof, so that the bail 38 will lock the door 2 in the closed position, as clearly appears in Figs. 2, 3, 5 and 6 of the drawings. A longitudinally or vertically arranged supporting strap 40 is also provided for supporting the device upon the clothing in a substantially usual manner with the exposed lamp at the front of the casing 1 directed away from the body of the person carrying the device, this supporting strap 40 being carried by and shown as secured to the back of the casing door 2. Near the upper free end of the door 2, the carrying strap 40 is secured thereto by means of the same two eyelets or tubular rivets 30 by which the supporting and insulating plates 28 and 29 of the spring bridge piece 26 are secured at the inner side of the door 2, as has been hereinbefore described. Near the lower or hinged end of the door 2 the carrying strap or supporting strap 40 passes freely through a transversely extending metal loop 41, the ends of which are firmly secured to the door 2, being shown in the drawings as held by eyelets forming rivets. Just above the two bridge-supporting and strap-securing rivets or eyelets 30, the strap 40 passes through the folded bail 38, so that this strap 40 acts as a guard to hold the bail 38 in its locking position relatively to the door 2, for securely locking the hinged

door 2 of the casing box 1 in its closed and circuit-completing condition, as clearly appears in the drawings, particularly in Figs. 2, 3, 5 and 6 thereof.

- 5 For carrying the device, the supporting strap 40 is adapted to be attached to the clothing of a person in two different ways. Adjacent to its free ends the strap 40 is provided with a two-part snap fastener, 10 shown as of the glove fastener type, and having a stud part 42 shown as secured to the upper end of the strap 40, and having a socket part 43 fixed upon the other or lower end of this strap. The upper end of the 15 strap 40, carrying the stud member 42 of the snap fastener, is adapted to be folded downward from the bail 38, and similarly the lower end of the strap 40 carrying the socket member 43 of the snap fastener is 20 adapted to be folded upward from the loop 41, for bringing the two parts 42 and 43 of the snap fastener into engagement, this condition being most clearly illustrated in Figs. 2 and 3 of the drawing. When the 25 two snap fastener parts 42 and 43 are thus engaged, the strap 40 forms a loop between the bail 38 at the top and the metal loop 41 at the bottom, and the usual belt of a person is adapted to pass through this loop 30 formed by the strap 40, for supporting the device upon the person. In the construction illustrated in the drawings, the distance between the loop formed by the folded bail 38 and the metal lower loop 41 is made such 35 that the closed loop formed by the supporting strap 40 is of the correct length or dimension for snugly accommodating the usual infantry belt of a United States soldier, and in view of the fact that the belts worn 40 in other branches of the military service are of narrower width, any one of these belts also will be equally well accommodated, as will also the usual belts worn by private citizens.
- 45 The supporting strap 40 also is provided adjacent to its ends, but inwardly from the snap fastener parts 42 and 43, with similar upper and lower button-holes 44 and 45, respectively. By disengaging the snap fastener parts 42 and 43, the strap 40, still passing through the folded bail 38, locking the door 2 in the closed position, may be straightened out and the button-holes 44 and 45 may then be buttoned over or engaged 50 with corresponding buttons upon a garment. In the device illustrated in the drawings, these button-holes 44 and 45, in the straightened out condition of the strap 40, are spaced apart the correct distance for engaging with two adjacent buttons of a soldier's coat. These button-holes, however, 55 may be similarly engaged with the buttons on any garment regardless of whether or not such buttons happen to be spaced apart 60 precisely or exactly the same distance as

are the button-holes 44 and 45, as will be readily understood by reason of the flexible character, both of the strap 40 and of material of the garment. In cases where it is desired to engage these button-holes with 70 two buttons which are comparatively close together, the upper end of the strap, having therein the button hole 44, may be straightened out, and the lower end of the strap, having therein the button-hole 45, may be 75 folded upwardly in the same position for this end as appears in the drawings, thereby bringing the two button-holes 44 and 45 considerably closer together than they are when both ends of the strap 40 are straightened out as hereinbefore described, and in such case the device will be likewise securely supported upon the garment of the wearer.

80 Although the self-contained portable electric light or flashlight of my invention illustrated in the accompanying drawings and above particularly described, is more particularly intended and adapted for the use of soldiers, yet it is to be understood that it 85 is an all-purpose device, having features and advantages adapting it also for general usage, and that the features of my invention hereinbefore described impart to the device certain advantages not heretofore obtained and adapt the device to new 90 uses not heretofore provided for in prior constructions.

95 In addition to the uses hereinbefore mentioned, it is to be noted that the flat bottom 100 of the casing box 1 permits the device to be stood upon its lower end and thus used as a reading lamp or for other purposes in a similar manner to an ordinary lantern or lamp. Also the device may be suspended 105 or hung up on any convenient hook, nail or other projection by means of the bail 38. The entire device is shapely and compact and may be conveniently packed in a soldier's kit to form an important item there- 110 in, or in any traveling bag, suitcase or other receptacle, and also, if desired, may be readily slipped into a pocket of a garment.

115 It is obvious that various modifications may be made in the construction shown in the drawings and above particularly described within the principle and scope of my invention.

I claim:

- 120 1. A portable electric light having in combination, a flat battery-containing casing open at the back, a lamp socket fixedly carried by the casing at the front and at the upper margin thereof and arranged to expose the lamp bulb at the outside of the flat 125 front side of the casing, an openable closure for the back of the casing, and a circuit-completing bridge carried by the closure and adapted to complete the circuit 130 from the central terminal of the lamp to

one of the terminals of the battery when said closure is in the closed condition.

2. A portable electric light having, in combination, a flat battery-containing casing open at the back, a lamp socket fixedly carried by the casing at the front and upper margin thereof and arranged to expose the lamp bulb at the outside of the flat front side of the casing, a circuit-completing member carried by the casing at the inside thereof and forming an electrically conductive extension of one of the battery terminals, an openable closure for the back of the casing, and a circuit-completing bridge carried thereby and adapted electrically to connect said circuit-completing member and the central terminal of the lamp in the closed condition of said closure.
3. A portable electric light comprising a flat battery-containing casing open at the back, a lamp socket fixedly carried by the casing at the front and upper margin thereof and arranged to expose the lamp bulb at the outside of the flat front side of the casing, a circuit-completing member carried by the casing at the inside thereof and forming an extension of one of the terminals of the battery, a hinged door for closing the back of the casing, a circuit-completing bridge carried by the door and adapted electrically to connect the central terminal of the lamp with said circuit-completing member carried by the casing in the closed condition of the door, and circuit-completing means for connecting the other terminal of the lamp with the remaining terminal of the battery, such means including a manually operable circuit-controller on the casing.
4. The invention claimed in claim 3 in which said circuit-controller comprises a spring metal strip forming a contact spring secured at one of its ends to the casing and projecting in an opposite direction to the battery terminal so that its other end is in proximity to and overlaps the battery terminal in spaced relation thereto, and a manually operable device movably supported by the casing and adapted when operated to engage and press upon said spring contact strip at an intermediate point thereof for thereby moving its free end into circuit-completing contact with the battery terminal.
5. The invention claimed in claim 3, in combination with a bail pivoted to one end of the casing and adapted to fold backward over the end of the closed door, and a supporting strap carried by the outside of the door and adapted to pass through the folded bail for thereby locking the door in the closed position.
6. The invention claimed in claim 4, in combination with a bail pivoted to the

top of the casing and adapted to fold backward over the upper end of the closed door, and a supporting strap carried by and secured to the outside of the door and adapted to pass through the folded bail for thereby locking the door in the closed position. 70

7. A portable electric light comprising a flat metallic battery containing casing open at the back, a metallic lamp socket fixedly carried by the casing at the front and upper margin thereof and arranged to expose the lamp bulb at the outside of the front of the flat casing, a circuit-completing sheet metal plate secured to the top of the inside of the casing and insulated therefrom and adapted 75 to be engaged by one of the terminals of the battery, a metallic door forming a closure for the back of the casing and hinged at the bottom to open backward and downward and provided at the top with a latch engageable with the casing, the central terminal of the lamp being exposed at the inside of the casing adjacent to but spaced from the door and the said circuit-completing plate having a part in proximity to but 80 spaced from the door, a metallic spring strip forming a bridge secured at an intermediate point thereof to the inside of the door and insulated therefrom and having inwardly offset spring ends one of which is 85 engageable with the central terminal of the lamp and the other of which is engageable with the said metallic contact plate when the door is in the closed condition, a bail pivoted to the top of the casing and adapted 90 to fold rearward over the upper end of the closed door, a supporting strap secured to the back of the door and adapted to pass through the folded bail for locking the door 95 in the closed and latched condition, a metallic spring strip secured at its upper end to the inside of the top of the casing and projecting downward into proximity with the other terminal of the battery, and a manually operable circuit-controlling member 100 movably carried by the casing and adapted to be operated to press against the downwardly projecting spring strip at an intermediate point thereof for shifting the free lower end of said spring strip into contact 105 with the other terminal of the battery, whereby the circuit of the lamp through the battery will be completed. 110

8. The invention claimed in claim 7 in which the downwardly projecting spring 115 contact strip is out of contact with and insulated from the metallic casing and is adapted to be electrically connected with the casing by the manually operable circuit-controlling member. 120

9. A portable electric light having, in combination, a casing for a battery having a projecting contact terminal, an automatically-returning movement-multiplying metal lever secured at one of its ends to the casing 130

and having a free end part projecting in a direction substantially opposite to and overlapping the battery terminal in spaced relation thereto, and a manually operable circuit-controlling member movably carried by the casing and adapted to be operated to press against said lever for shifting the free end part of said lever into contact with the adjacent terminal of the battery.

10. A portable electric light having, in combination, a metallic casing adapted to contain a battery having a projecting contact terminal, a flexible spring metal lever firmly secured at one of its ends to the casing and insulated therefrom and having a free end part projecting in a direction substantially opposite to and overlapping the battery terminal in spaced relation thereto, and a manually operable circuit-controlling member in electrical connection with and movably carried by the casing in spaced relation to the flexible spring lever at a median point thereof and adapted to be pressed against and into electrical connection with said median point of the spring lever for shifting the free end part of the spring lever into electrical connection with the adjacent terminal of the battery.

15. A portable electric light having, in combination, a flat battery-containing casing open at the back, a lamp socket fixedly carried by the casing at the front and margin thereof and arranged to expose the lamp bulb at the outside of the flat front side of the casing, an openable closure for the back of the casing, and a circuit-completing bridge carried by the closure and adapted to complete the circuit from the central terminal of the lamp to one of the terminals 20 of the battery in the closed condition of said closure.

20. A portable electric light having, in combination, a flat metallic battery-containing casing open at the back, a lamp socket carried by the casing at the front and margin thereof and arranged to expose the lamp bulb at the outside of the flat front side of the casing, an openable metallic closure for the back of the casing, inner and outer superposed insulating plates at the inside of said metallic closure, a supporting strap at the outside of said metallic closure, fastening devices passing through the superposed insulating plates and through said metallic closure and through the supporting strap for securing the insulating plates and the supporting strap to said metallic closure, a metallic bridge carried by the inner insulating plate at the inner side thereof for completing the circuit from the central terminal of the lamp to one of the terminals of the battery in the closed condition of said metallic closure, and a metallic fastening device passing through the bridge and 30 through the inner insulating plate and in-

sulated from said metallic closure by the outer insulating plate for supporting the bridge on said metallic closure and insulating it therefrom.

13. The invention claimed in claim 11 in which the closure is a hinged door, in combination with a bail pivoted to the top of the casing to fold backward over the upper end of the door, and a supporting strap at the outside of the door adapted to pass through the folded bail for locking the door in the closed position.

14. The invention claimed in claim 12 in which the metallic closure is a door hinged at its lower end, in combination with a bail pivoted to the top of the casing to fold backward over the upper end of the door and through which the supporting strap is adapted to pass for locking the door in the closed position.

15. A portable electric light having, in combination, a flat battery-containing casing open at the back, a hinged door for the back of the casing, a bail pivoted to the top of the casing to fold backward over the upper end of the door, and a supporting strap at the outside of the door adapted to pass through the folded bail for locking the door in the closed position.

16. A portable electric light having, in combination, a casing divided into openable parts, a supporting strap at the outside of one of the casing parts, and means carried by the other casing part and engaged by the strap for holding the casing in the closed condition.

17. A portable electric light having, in combination, a metallic casing adapted to contain a battery having projecting contact terminals, superposed inner and outer insulating plates at the inside of the top of the metallic casing and secured thereto, a circuit-completing metal plate at the inside of the inner insulating plate and supported thereby in position to be engaged by and form an electrical extension of one of the projecting terminals of the battery, a metallic fastening device passing through said circuit-completing plate and through the inner insulating plate and insulated from the metallic casing top by the outer insulating plate, a spring metal lever also at the inside of the inner insulating plate and supported thereby and having a free end part projecting in a direction substantially opposite to and overlapping the other projecting battery terminal in spaced relation thereto and also in spaced relation to the metallic casing, a metallic fastening device passing through said lever and through the inner insulating plate and insulated from the metallic casing top by the outer insulating plate, and a manually operable circuit-controlling member in electrical connection with and movably carried by the casing in

spaced relation to the spring lever and adapted to be pressed against the spring lever for forming an electrical connection therewith and for shifting the free end part 5 of the spring lever into electrical connection with the adjacent terminal of the battery.

18. A portable electric light having, in combination, a battery-containing casing open at one side, a hinged door for the casing, and a bail pivoted on the casing and in 10 its folded position engageable with the door for locking the door in the closed position.

19. A portable electric light having, in combination, a flat battery-containing casing open at the back, a door hinged at its 15 lower end for closing the back of the casing, and a bail pivoted to the top of the casing and having a part engageable at the back of the upper end of the door in the folded position of the bail for locking the door in 20 the closed position.

In testimony whereof I have affixed my signature.

BERNARD BENEDICT.
